ATTORNEY

UNITED STATES PATENT OFFICE

WALTER HERMAN NOTZKE, OF PEKIN, ILLINOIS

COASTER

Application filed October 14, 1929. Serial No. 399,564.

This invention relates to toys, an object of the invention being to provide a wheeled toy of the coaster type which may be readily steered to control its direction of travel, or which may be pulled by means of a tongue or handle after the manner of a toy wagon.

To this end, the invention provides a novel form of steering mechanism which may be readily operated, and which will remain in position until purposely changed, so that the toy will, when used as a coaster, travel a given direction until a change is desired by the rider.

The invention further provides means for mounting the handle so that it may be extended for use, or stored beneath the platform, means being provided for holding the handle in stored position.

With the above and other objects in view, the invention further includes the following novel features and details of construction, to be hereinafter more fully described, illustrated in the accompanying drawings and pointed out in the appended claims.

In the drawings:—

Figure 1 is an elevation of the toy with the handle extended.

Figure 2 is an enlarged sectional view with the handle in stored position.

Figure 3 is a bottom plan view with the parts in the position shown in Figure 2.

Figure 4 is an enlarged sectional view taken substantially on the line 4—4 of Figure 2.

Figure 5 is a section on the line 5—5 of Figure 4.

Referring to the drawings in detail wherein like characters of reference denote corresponding parts, the reference character 10 indicates the platform of the toy, and while only a platform is shown, it is obvious that side and end members may be removably or otherwise attached to the platform so as to provide a wagon box or body.

The platform is mounted upon rear wheels 11 and the front wheels 12. The rear wheels are mounted upon the ends of an axle 13 and the latter is mounted in a substantially rectangular frame 14 which extends downward and is disposed transversely of the

body. Bolts or other means 15 serve to secure the frame 14 to the platform. Inclined braces or hounds 16 connect the frame 4 and the platform and serve to steady and stabilize the frame.

The wheels 12 are mounted upon an axle 17 and this axle is in turn mounted in the frame 18 similar to the frame 14. The frame 14 however is rigid with the platform, while the frame 18 is pivotally attached thereto as shown at 19, so that the wheels 12 provide steering wheels. Braces or hounds 20 connect the frame 18 with the platform 10.

Extending outward from the front end of the platform is a substantially U-shaped member or loop 21. The inner ends of this member are secured to opposite faces of the platform as shown at 22, while the outward forward portion of the loop is beveled or inclined as shown at 23. This end of the loop or member 21 is longitudinally slotted as at 24 and slidable within this slot is a headed member 25 which carries a transversely arranged loop 26.

A tongue 27 is slidable within the loop 26 and may be extended as shown in Figure 1 of the drawings, studs 28 serving to limit sliding movement of the tongue in one direction. When in the position as shown in Figure 1 of the drawings, the headed stud 25 is slid upward along the inclined portion of the slot 24 so that the loop 26 will be inclined.

The handle 27 is adapted to be stored beneath the bottom of the platform and for this purpose a loop member 29 is secured beneath the platform to receive the inner end of the tongue. The outer end of the tongue is provided with a cross member or handle 30. A spring finger 31 which extends from this cross member or handle is designed to be extended through the slot 24 and yieldingly engage the U-shaped member 21 to prevent accidental outward sliding movement of the tongue.

Pivotedly mounted between the arms of the U-shaped member 21 is a steering bar 32. Pivotedly connected to the bar 32 as shown at 33 are the outer ends of links 34. The inner ends of these links are pivotally connected to the frame 18 as shown at 35, so that pivotal

100

movement of the bar 32 will move the frame 18 pivotally and consequently move the wheels 12 so as to control the direction of travel of the toy.

5. Mounted upon the pivot 36 which serves to pivotally secure the bar 32 within the U-shaped member 21 is a spring member 37. This member is provided with a sleeve or thimble 38 which surrounds the pivot 36.
10. The opposite ends of the spring member 37 bear upon the bar 32 and are held in position upon this bar by means of offset portions 39 which enter pockets 40 provided in the bar.

This spring member thus frictionally engages the upper arm of the member 21 and forces the lower face of the bar 32 into frictional engagement with the lower arm of the member 21. The steering bar 32 will thus be evenly held against pivotal movement so that the steering wheels 12 will remain in adjusted position until purposely changed.

The thimble 38 is transversely rectangular, and the pivot 36 is provided with a similarly shaped portion 44, which passes through a rectangular opening in the member 21 to prevent the spring from turning when turning the steering bar.

The invention is susceptible of various changes in its form, proportions and minor details of construction and the right is herein reserved to make such changes as properly fall within the scope of the appended claims.

Having described the invention what is claimed is:—

1. In a toy, a wheel supported platform including pivotally mounted front steering wheels, an elongated substantially U-shaped member extending forwardly from the platform, a pivot pin extending transversely through the arms of said member, a steering bar having spaced sockets therein mounted for pivotal movement between said arms upon said pin, means operatively connecting the steering wheels and bar, oppositely extending spring arms mounted upon the pivot pin between the arms of the U-shaped member and bar, and means extending from the spring arms to yieldingly engage within the sockets and yieldingly hold the steering bar against accidental movement.

2. In a toy, a wheel supported platform including pivotally mounted front steering wheels, a steering bar, means operatively connecting the steering bar and steering wheels to move the latter pivotally when the steering bar is operated, means to pivotally support the steering bar from the platform, a handle, means carried by the steering bar support to slidably receive the handle, whereby the latter may be extended or stored beneath the platform, and means to hold the handle in stored position.

3. In a wheeled toy, a platform, a projection extending forwardly from the platform,

a loop slidably secured to the extension, a handle slidable within the loop, whereby the handle may be slid beneath the platform, means beneath the platform to engage and support the handle, and means to hold the handle against outward sliding movement when said handle is disposed beneath the platform.

In testimony whereof I affix my signature.
